UNITED STATES PATENT OFFICE.

ERASTUS G. MOORE, OF LONG BEACH, CALIFORNIA.

DESIGN FOR AN AEROPLANE-COASTER.

55,636.

Specification for Design.

Patented July 6, 1920.

Application filed December 11, 1919. Serial No. 344,152. Term of patent 7 years.

To all whom it may concern:

Be it known that I, ERASTUS G. MOORE, a citizen of the United States, residing at Long Beach, in the county of Los Angeles and State of California, have invented a new, original, and ornamental Design for an Aeroplane-Coaster, of which the following is a specification, reference being had to the accompanying drawing, forming part thereof.

Figure 1 is a rear perspective view of my aeroplane coaster, showing my new design; and

Fig. 2 is a front perspective view of the same.

I claim:

The ornamental design for an aeroplane coaster, as shown.

Signed at Long Beach, California, this 3d day of December, 1919.

ERASTUS G. MOORE.
